UNITED STATES PATENT OFFICE.

CHARLES H. GUNN, OF MARYSVILLE, CALIFORNIA.

DREDGER AND SCRAPER.

No. 876,634.

Specification of Letters Patent.

Patented Jan. 14, 1908.

Application filed May 1, 1907. Serial No. 371,348.

To all whom it may concern:

Be it known that I, CHARLES H. GUNN, a citizen of the United States, residing at Marysville, in the County of Yuba and State of California, have invented certain new and useful Improvements in Dredgers and Scrapers; and I do declare the following to be a full, clear, and exact description of the same such as will enable others skilled in the art to which it appertains to make and use the same, reference being had to the accompanying drawings, and to the characters of reference marked thereon, which form a part of this specification.

This invention relates to improvements in dredging and scraping machines, the object of the invention being to produce such a machine as will automatically scrape the earth and advance the same to an elevating conveyer, dump the same onto said conveyer, immediately rise clear of such conveyer, and return to a scraping position again, all of said movement, including the movement of the conveyer, being simultaneous and co-operative and actuated by a single actuating means. This main object and many minor ones I accomplish by means of drive wheels having pitmen pivotally secured thereto, means for oscillating or vibrating said pitmen, a scraper arranged in operative connection with said pitmen, and an elevating conveyer operated by the movement of said drive pulleys and arranged in operative connection with said scraper, also by such other and further construction as will appear by a perusal of the following specification and claims.

In the drawings similar characters of reference indicate corresponding parts in the several views.

Figure 1 is a side elevation of the complete device. Fig. 2 is a longitudinal section of the device. Fig. 3 is a sectional view taken on a line xx of Fig. 1. Fig. 4 is a front elevation of a serrated spading bar.

Referring more particularly to the characters of reference on the drawings 1 designates base beams. Across the under sides of the said beams 1 near the front thereof is a cross beam 2 in the center of which is journaled a roller 3.

4 are inclined beams secured to the rear of the beams 1 and supporting at their upper ends inclined beams 5, said beams 5 being secured to the beams 1 at their lower ends. Secured to the beams 4 is a cross beam 6 at

the ends of which beam 3 are journaled supporting wheels 7. Secured across the beams 1 near the rear thereof is a platform 8 on which is stationed an engine 9; the shaft 10 from the crank having a worm gear 11 secured thereto and intermeshing with a screw gear 12 on a shaft 13 journaled on supports 14, on the ends of which shaft 13 are secured sheave pulleys 15. Cables or straps 16 connect the pulleys 15 with larger sheave pulleys 17 secured on a shaft 18, which shaft 18 is journaled across the top ends of the beams 5. Secured to the shaft 18 between the beams 5 is a roller 19.

20 and 21 are suitable cross braces and cross beams joining the beams 5. Journaled between the beams 5 at their lower ends is a roller 22. Disposed over the rollers 19 and 22 is a conveyer belt 23, the same resting on concave rollers 24 disposed between the beams 5, all for a purpose as will appear. Secured to the sides of the beams 5 near the lower ends thereof are metal side plates 24 and upward from said plates 25 are beams 26 secured to the beams 5 by means of angle irons 27, said beams extending slightly over the edges of the conveyer belt 23. Secured between the lower ends of the beams 5 is an inclined plate 28, the same extending up over the belt 23. Tied to the beams 1 and 5 by U-shaped ties 29 are slightly inclined beams 30, the same being tied at the top end by means of cross beam 31 and cross rod 32. Journaled between the beams 30 above the beams 5 is a roller 33. Secured in the rims of the pulleys 17 are wrist pins 34 on which are pivotally mounted pitmen 35, said pitmen extending along side of and beyond the beams 30. Tied to the outer ends of the pitmen 35 are cross beams 36 and tied to the said pitmen 35 to the rear of the beams 30 are higher cross beams 37. Tied to the beams 36 and 37 are longitudinal beams 38 provided with bottom iron rails 38^a, which beams 38 extend over the roller 33 and between the beams 30. On the outer ends of the beams 38 is secured a scraper 39 having a removable blade 40 and strengthening chains 41 connecting the lower part of said scraper to the beams 38. Held outward from the rear of said scraper is a serrated spading bar 42 for the purpose as will appear. To the rear of the roller 19 is secured a hopper 43 having side chutes 44.

In practice the pitmen 35 are secured to the pulleys 17 at such points and will produce the following motion:—Presuming the

pitmen to be in their lowest position as shown at *a* in the drawings, the beams 38 are resting on the rollers 33. The pulleys 17 revolve rearward, thus advancing and raising the pitmen 35 to a point as at *b*, thus raising the beams 38 from the roller 33 and thus causing the whole weight of the pitmen and their parts to fall on the scraper 39. When this position is reached the scraper 39 is 10 adapted to engage with the earth. The pitmen are then, by rotation of the pulleys 17, pulled backward and upward to a point as at *c*, which action pulls the scraper along the ground up to the incline 28, filling the bowl 15 of the scraper with dirt and depositing it on the conveyer 23. The rotation of the pulleys 17 then pull the pitmen to the position *a*, thus causing the beams 38 to rest on the roller 33, which action lifts the scraper 39 20 immediately upward ready for another drive. Thus it will be seen that the motion just described is most advantageous in that the most possible weight is thrown on the scraper 39 just as it is to perform its scraping function, thus making the same more effective. Then when its function is performed it immediately rises clear of the machine ready for another operation. The purpose of having the pitmen 35 extend outside of the beams 30 30 and the beams 38 inside is to permit a freedom of motion to the pitmen and a restricted motion to the beams 38 by the roller 33 as described. The member 33 by means of the members 36—37 and 38 holds the pitmen in 35 suspension, thus restricting the movement thereof to cause the scraper 39 to properly engage with the plate 28. The pulleys 17 and wrist pins 34 perform the functions of cranks in oscillating and reciprocating the 40 pitmen 35, hence in the claims I have employed this designation in claiming these elements.

The serrated bar 42 extending to the rear of the scraper 39 tends to spade and loosen 45 the earth while the scraper is performing its functions, thus rendering it more easily handled by said scraper. As the earth is deposited upon the belt 23 it is conveyed upward, the oval shaped rollers 24 and the side 50 member 25 and 26 forming a trough and holding the earth in the center of said belt, thus preventing it from falling off the edges. As the earth reaches the top of the belt 23 it is 55 deposited in the hopper 43 and then distributed through the chutes 44 to any desired point. By reason of the binding irons 29 the beams and their parts may be moved to any desired position. The roller 3 permits the front of the machine to be easily turned 60 in any desired direction.

Thus it will be seen that I have produced a device which is invaluable for dredging and scraping and particularly for ditch making and grading, the whole machine and the 65 movement thereof being extremely simple

yet admirably adaptable for the purpose for which it is designed.

While in this specification I have set forth in detail the present and preferred construction of my invention, still in practice many 70 small deviations therefrom may be resorted to in practice without departing from the spirit of my invention.

Having thus described my invention what I claim as new and useful and desire to secure 75 by Letters Patent is:—

1. In a device of the character described an inclined conveyer, drive pulleys journaled at the top thereof, means for rotating said pulleys, pitmen pivotally secured to the rims 80 of said pulleys, a scraping means in operative connection with said pitmen, and means whereby oscillating movement imparted to said pitmen will cause said scraper to cut and draw earth to said conveyer, as specified. 85

2. In a device of the character described a frame, cranks journaled therein means for rotating the same, pitmen pivotally secured to said cranks, a scraping means secured to said pitmen, and means restricting the oscillation of such pitmen, as described. 90

3. In a device of the character described, base beams, upright beams movably secured to said base beams, a roller disposed between said upright beams, cranks held upward 95 from said base beams, means for driving said cranks, pitmen pivotally secured to said cranks and extending along the outside of said upright beams, cross beams on said pitmen disposed to the front and rear of said 100 upright beams, longitudinal beams secured to said cross beams and extending over said roller and between said upright beams, a scraper secured to the outer ends of said longitudinal beams, and a conveyer in operative 105 connection with said scraper, as specified.

4. In a device of the kind described a conveyer, an oscillating scraper in operative connection therewith and a spading bar held outward from the rear of said scraper, as specified. 110

5. In a device of the character described a conveyer, an oscillating scraper in operative connection therewith and a serrated spading bar held outward from the rear of said 115 scraper, as specified.

6. In a device of the character described base beams, a cross beam secured to the under side thereof near the front end, a roller journaled in said cross beam, supporting wheels 120 secured to the rear end of said beams, an inclined conveyer held upward from said beams and an oscillating scraping means in operative connection with said conveyer, as described.

7. In a device of the character described base beams, inclined beams held upward therefrom, rollers disposed between said inclined beams at intermediate points thereof, a conveyer belt disposed over said rollers, side plates secured to said inclined beams 125 130

near their lower ends, side beams upward from said plates and secured to said inclined beams by angle irons and extending slightly over the edges of said conveyer belt, and a 5 scraper in operative connection with said conveyer, as specified.

8. In a device of the character described base beams, a cross beam secured to the under side thereof near the forward end, a 10 roller journaled in said beams, supporting wheels secured to the rear ends of said base beams, a platform secured at the rear ends of said base beams, an engine secured to said platform, a worm gear secured to the crank 15 shaft of said engine, said worm gear intermeshing with a screw gear secured on a shaft held upward from said platform, sheave pulleys secured to said shaft, inclined beams held upward from said base beams, a shaft 20 journaled in the upper ends of said inclined beams, sheave pulleys secured to said shaft, cables connecting said first and last named pulleys, a roller secured on said last named shaft, a roller disposed between said inclined 25 beams at their lower ends, a conveyer belt disposed over said rollers, pitmen pivotally secured to the rims of said last named pulleys,

means for regulating the oscillation of such pitmen as desired, and a scraper secured to said pitmen, as set forth.

30

9. In a device of the character described a frame, cranks journaled therein, pitmen pivotally secured to said cranks, a scraping means in connection with said pitmen, and means holding said pitmen in suspension, as 35 set forth.

10. In a device of the character described, a frame consisting of base beams and inclined beams upward therefrom, cranks held upward by such inclined beams, pitmen pivotally mounted on said cranks, a scraping means in connection with said pitmen, upright members movably secured to said base beams, a roller disposed between said upright members, and means whereby said pitmen are held in suspension on said rollers, as 40 45 set forth.

In testimony whereof I affix my signature in presence of two witnesses.
